COMBINED ASH TRAY AND SIGNAL

John Francis Walsh and Daniel Webster,
Chicago, Ill.

Application April 21, 1950, Serial No. 9,406

Term of patent 14 years

(Cl. D85—2)

To all whom it may concern:

Be it known that we, John F. Walsh and Daniel Webster, citizens of the United States, residing at 3754 Magnolia Avenue, Chicago 13, Illinois, and 1261 Ardmore Avenue, Chicago 40, Illinois, respectively, have invented a new, original, and ornamental Design for a Combined Ash Tray and Signal, of which the following is a specification, reference being had to the accompanying drawing, forming part thereof.

Fig. 1 is a side elevational view of a combined ash tray and signal showing our new design; and Fig. 2 is a top plan view thereof.

We claim:

The ornamental design for a combined ash tray and signal, as shown.

JOHN F. WALSH.
DANIEL WEBSTER.
